UNITED STATES PATENT OFFICE

153,443

DESIGN FOR A WASTE RECEPTACLE

Robert L. Moore, Memphis, Tenn., assignor
to Binswanger-Henkin Industries, Memphis,
Tenn., a partnership.

Application January 27, 1947, Serial No. 136,452

Term of patent 14 years

(Cl. D58—17)

To all whom it may concern:

Be it known that I, Robert L. Moore, a citizen of the United States of America, residing at Memphis, in the county of Shelby and State of Tennessee, have invented a new, original, and ornamental Design for Waste Receptacles, of which the following is a specification, reference being had to the accompanying drawings, forming part thereof.

In the drawings:

Fig. 1 is a front perspective view of a waste receptacle, showing my new design.

Fig. 2 is a rear elevational view thereof,

Fig. 3 is a front elevational view thereof, and

Fig. 4 is a side elevational view thereof, the opposite side having substantially the same appearance.

I claim:

The ornamental design for a waste receptacle, as shown and described.

ROBERT L. MOORE.
